UNITED STATES PATENT OFFICE.

ERNEST E. HEINTZ AND THOMAS P. ARCHER, OF DETROIT, MICHIGAN, ASSIGNEES TO
TERNSTEDT MANUFACTURING COMPANY, OF DETROIT, MICHIGAN, A CORPORATION OF MICHIGAN.

WINDOW-SASH CHANNEL.

Application filed June 28, 1924. Serial No. 723,062.

To all whom it may concern:

Be it known that we, ERNEST E. HEINTZ and THOMAS P. ARCHER, citizens of the United States, residing at Detroit, in the county of Wayne and State of Michigan, have invented certain new and useful Improvements in Window-Sash Channels, of which the following is a specification.

This invention relates to window sash channels and has for its object a window sash channel that can be rolled from a single piece to form the glass-receiving channel and provide a guide for the lifting element of a regulator. This makes a single, integral structure which can be rolled in continuous lengths at relatively great speed on machines similar to tube forming machines. The bottom of the glass-retaining channel at the same time forms the top of the guide channel for the lifting element. The strip being rolled in this way, the parts are always automatically furnished of the proper size and properly located with respect to each other. This makes the manufacture of the structure that has these functions very much cheaper and very much more reliable and accurate than when the parts are separately formed and secured together either by riveting, spot-welding, or otherwise.

Referring to the drawings:

Fig. 1 is an elevation of the window sash with our improved sash bar secured thereto, showing a portion of the regulator for raising or lowering the window.

Fig. 2 is a vertical section through the sash bar.

Fig. 3 is a vertical section showing a modified form of construction.

Fig. 4 is a detail perspective view of the sash bar shown in Fig. 2.

a designates the window provided with a lower sash bar *b*, which is rolled in continuous lengths on a machine with suitable rolls and mandrels, or suitable rolls, dies and mandrels. This rolling operation is performed on strip stock of suitable width, continuously fed through the rolls and formed into the shape shown in the draw-

ings. The strip stock is shaped by these rolls to provide an upwardly facing channel and a laterally facing channel below the upwardly facing channel. The upwardly facing channel is preferably provided with an inverted V groove in the bottom of the channel designated *g*. The metal stock after forming the upwardly presenting channel is folded down along the outside wall of this channel and formed in a relatively long *L*. This provides an inwardly presenting guide channel *c*. The roll *f*, which has a periphery convex in cross section, is rotatably secured on the lever arm *e* of the lever type regulator. This lever arm *e* is secured to the toothed quadrant and the quadrant may be raised or lowered in a familiar way in the art relating to window regulators.

This particular channel with the inverted V groove at the bottom of the upwardly presenting channel is especially adapted for use with this roll type of window lifting element secured on a lever. Such a channel must needs run nearly the width of the window and furthermore, by simply tilting the window sash, the channel may be disengaged from the side of the roll, but only by tilting may it be so disengaged for in the form shown in Fig. 2, it will be seen that the V groove locks over the roller, preventing removal of the same by side draft. It will therefore be apparent that when the garnish moulding (not shown) in the window is taken out so that the window can be tilted, the window may be easily disengaged from the roll. However, when the garnish moulding is in place, the shape of this channel securely locks the channel and the roll together. In fact, when the roll is assembled in the channel, the channel is slightly sprung as shown exaggeratedly in Fig. 2, so as to take up all looseness and rattle.

What we claim is:

1. A sash lower channel bar, comprising a single strip of stock fashioned into an upwardly presenting channel to take the glass and having a depending L-like portion doubled back on one side wall of the upwardly

presenting channel to form a laterally opening channel to guide a regulator element.

2. A sash lower channel bar, comprising a single strip of sheet metal stock fashioned with an upwardly presenting channel having an inverted V-like bottom portion and having a continuation in the form of an L dou-

bled back on one wall of the upwardly presenting channel and forming a laterally presenting channel for the purpose specified.

In testimony whereof we have affixed our signatures.

ERNEST E. HEINTZ.
THOMAS P. ARCHER.
